(57) CLAIM

The ornamental design for a concealing cover-up with integrated pockets, as shown and described.

DESCRIPTION

FIG. 1 is a front perspective view of the concealing cover-up with integrated pockets showing a unique design.

FIG. 2 is an angled perspective rear view thereof;

FIG. 3 is a front elevational view thereof;

FIG. 4 is a left-side elevational view thereof;

FIG. 5 is a rear elevational view thereof; and,

FIG. 6 is a right-side elevational view thereof.

The large dashed lines are used to illustrate the human wearing the article and do not form any part of the claimed design. The small dashed lines parallel to the edges of the article show a portion of the article, and do not form any part of the claimed design. The large dashed lines indicating the two pockets that are integrated within the article and do form part of the claimed design of the article.

1 Claim, 6 Drawing Sheets
